ROOFING

William Wallace Rowe, Cincinnati, Ohio, assignor to Cincinnati Industries, Inc., Lockland, Ohio, a corporation of Ohio

Application April 19, 1947, Serial No. 742,627

4 Claims. (Cl. 154—51)

This application is a continuation-in-part of my copending application, Serial No. 389,961 of the same title, filed April 23, 1941, now abandoned.

My invention pertains to roofing in which the resistance of the structure to water and weather depends upon the use of bitumen or equivalent substance in a heavy, discrete layer serving as a waterproof membrane.

In the manufacture of current prepared roofing a dry felt, which is a relatively heavy, porous, felted sheet containing a considerable percentage of rag fibers is saturated with a saturating type asphalt, then coated with a heavy continuous layer of a relatively non-saturating type asphalt.

Built-up roofing is similar in general structure except that it is assembled on the job. Saturated felt is nailed to a wooden deck or is mopped onto a concrete deck with hot asphalt; and a roof covering is built-up in plies mopped together by means of a high melting point asphalt. A top layer of the asphalt is also applied over the topmost layer of felt. In each instance, the weather resistance and waterproof character of the roofing is dependent upon the integrity and continuity of a relatively heavy layer of coating asphalt, or a plurality of such layers.

The coating of asphalt is not perfectly weather resistant, but is subject to a progressive deterioration. Under the influence of actinic light and the weather, the surface of the asphalt takes on a hard crusted condition, frequently referred to as an "oxidized" condition. The hard external crust cracks or crazes along a multitude of lines, exposing a fresh asphaltic surface at the cracks. This surface in turn becomes hard and crusted, and a continuation of the cracking and crazing deepens the cracks into canyons or valleys which eventually progress throughout the thickness of the asphaltic layer.

Covering substances such as the crushed slate frequently applied to prepared roofings and the gravel frequently applied to built-up roofings delay this action somewhat but do not prevent it. Since the utility of the roofing depends upon the integrity of a continuous, relatively heavy layer of asphalt or other bitumen, the result of this progressive deterioration adversely affects the life of such roofing materials.

The principal object of my invention is the provision of a roofing fabric or roofing structure which, while dependent for its effective life on the integrity of a heavy, continuous layer of bitumen or its equivalent, is nevertheless not subject to the rapid and progressive disintegration of such a layer in the manner described above, and hence has much longer life. It is an object of one aspect of my invention to provide protective means for roofing of otherwise conventional type to prevent or greatly delay the progressive destruction of the bituminous layer.

It is an object of other aspects of my invention to provide roofing fabrics which are not constructed like those heretofore known in the art, but have novel and improved structures as will hereinafter be set forth. My invention is applicable to the provision of prepared roofings or substitutes for prepared roofings which may be applied in roll form or in the form of cut pieces such as shingles or strips. It is also applicable to the production of prepared roofing materials or substitutes for them which may be employed on the job in the construction of so-called built-up roofs.

The invention is based upon my discovery that the association, with an otherwise exposed thick layer of

2

bituminous substance or its equivalent, of an external web which is universally contractible and expansible i. e., readily stretchable and contractible in all directions, acts to prevent the cracking and crazing aforesaid and hence the progressive deterioration of the said thick layer. The type of universally expansible web which I employ is one which has been gathered in a plurality of directions so as to be stretchable in all directions, and such a web is preferably formed by creping.

10 The weather resistance of the stretchable web by itself is not of fundamental importance. While cloth may be employed, I have found that creped paper is sufficient as a covering layer, and when so used will add years to the useful life of a roofing fabric. The universal stretchability is, however, a requirement, and webs which are not stretchable at all or are stretchable in but one primary direction will not serve to prevent the progressive disintegration of the bituminous layer.

Without wishing to be bound by theory, I nevertheless believe that the reason for the progressive disintegration of a bituminous layer in exposed roofing products, in view of the crusting action, is primarily a matter of expansion and contraction. The initial cracking or crazing of the so-called oxidized crust is due to expansion of the bituminous layer against the inexpandable crust. The expansion or contraction of a base or support bearing the bituminous coating is not of primary consequence although it may to some extent affect the expansion and contraction of the bituminous layer. When the cracks have once been formed, further oxidation of the bituminous surfaces in the cracks, accompanied by further expansion and contraction, works the cracks down into the body of the layer until presently along the lines of the cracks the body becomes completely cut through and the base is exposed to the weather.

40 A covering imposed upon a heavy bituminous layer, insofar as it protects the surface of the bituminous layer from the weather, oxidation and actinic light, might be expected to prevent the formation of the initial crust. But a non-expansive web, such as a web of plain paper or a web which is stretchable in but one direction, in adhesive union with a heavy bituminous layer, is itself subject to the expansion and contraction of the bituminous layer and will split or crack in one or a plurality of directions if subjected to expansion and will lose bond if subjected to contraction. When these cracks are formed, the oxidation of the bituminous layer occurs in them, and the action of the progressive deepening of canyons in the bituminous layer begins and continues to the complete destruction of that layer. This action is similar to the destruction of the bituminous layer under such discontinuous coatings as slate, sand, gravel or the like. A web which is universally expandable, however, follows the movements of the bituminous layer and does not itself crack. Hence, it not only prevents the formation of a general crust over the whole surface of the asphaltic layer, but prevents the formation of any exposed cracks which, being subject to crusting, could progressively deepen. It is further remarkable that an external layer of universally stretchable paper, in intimate adhesive association with a heavy bituminous layer seems to acquire a property of relative indestructibility from weathering. A piece of universally stretchable paper which, exposed by itself or with a thin coating of bitumen to the weather would rapidly disintegrate will, if associated throughout its area with a heavy, unitary layer of bitumen, retain for many years its bond and hence a sufficient integrity to protect that layer of bitumen from progressive disintegration, even though the paper is itself directly exposed to the weather. It is desired, however, the paper may itself be protected by a paint which has inherent elasticity or which follows the contours of the crepes.

75 In one aspect, it is an object of my invention to provide protection for hitherto known types of prepared roofings as aforesaid by providing in association with the normally exposed surface of a heavy layer of bituminous substance, an external covering which is a universally stretchable web. In another aspect of my invention, it is my object to produce improved roofing fabrics by as-

sociating two or more heavy layers of bitumen with intermediate and external universally stretchable webs.

I am aware that multiple products comprising universally stretchable webs adhered together by coatings of asphalt, with or without interior reinforcement, have been made in the art and have been used as building or wrapping papers. Because such papers have a certain degree of water resistance they would, if attached to a roof, give temporary protection against the weather. Such products, however, have consisted of the stretchable webs cemented together with such amounts of bitumen as are required for plying purposes. When subjected to the weather the useful life of these materials is extremely short. The product tends to delaminate, and the stretchable paper webs weather away and disintegrate. Because such bituminous coatings have no entity or integrity apart from the paper, they disintegrate physically along with the paper. The structure in the course of time becomes a pulpy mass and in effect washes away. Resistance to the weather such as is required in a product serving the purposes of commercial roofing is dependent upon a layer of bitumen so thick as to act as an independent and discrete entity apart from any base or covering with which it is associated. Such a layer of bitumen is, however, subject to its own independent flow or movement and expansion and contraction and, in the unprotected state, to the progressive disintegration which has been described and which it is an object of this invention to prevent or greatly delay.

These and other objects of the invention, which will be clear from what has been said above, which will be pointed out hereinafter, or which will be apparent to one skilled in the art upon reading these specifications, I accomplish in the structures and arrangement of parts of which I shall now describe certain exemplary embodiments.

Reference is made to the accompanying drawings, wherein:

Figure 1 is a partial cross-section of one type of roofing fabric made in accordance with my invention.

Figure 2 is a similar view showing an edge treatment thereof.

Figure 3 is a partial cross-sectional view of another type of roofing fabric made in accordance with my invention.

Figure 4 is a similar view showing an edge treatment thereof.

Figure 5 is a similar view showing another kind of edge treatment.

Figure 6 is a partial cross-sectional view of a built-up roof made in accordance with my invention.

Figure 7 is a diagrammatic elevational view showing an apparatus and method of providing seam forming means in connection with my roofing.

Figure 8 is a plan view of a piece of my roofing fabric showing seam forming means.

Figure 9 is a partial perspective view showing a mode of seam formation.

Figure 10 is a partial sectional view taken across the seam of Figure 9.

By a heavy discrete layer of bitumen, I mean a continuous layer of the substance of a thickness which enables it to leave its own mode of expansion, contraction, flow and movement irrespective of a support or covering web. In the prepared and built-up roofings of commerce, the asphalt coatings range approximately from 25 lb. to 50 lb. of the bitumen per 100 square feet (or "square" of 108 sq. ft.) of the roofing fabric. The saturated felt employed will usually be from 15 to 30 pounds per square. While this is a weight ratio of around 1:1 or in excess thereof, it will be understood that the layer of bitumen is thick in the absolute sense.

In the manufacture of building papers, a coating of plying asphalt on a paper web will normally have a ratio of 1:1 or less; but because paper does not compare in thickness with saturated felt, the layer of asphalt will be thin in the absolute sense.

In my products I associate a covering web of universally stretchable paper with a layer of bitumen which in weight or thickness will have a ratio to the paper of 3:1 or more in most instances. The independent flow action of a layer of bitumen will bear a relationship to the thickness of the paper; but in instances where a 3:1 or greater ratio is not maintained (as where an exceptionally heavy paper is chosen without a proportional increase in the

bituminous layer) I do not employ a bituminous coating less than about 8 lb. to 10 lb. per 100 square feet. It may be made thicker with improved results, the upper limit being a thickness, in view of the characteristics of the bitumen itself, which might permit creeping of the bituminous layer at high temperatures on a roof of the pitch for which a particular roofing is designed. The bitumen itself should be of the coating type as known in the roofing industry. A satisfactory exemplary asphalt is one having a ball and ring softening point of approximately 180-200 degrees F. and a penetration at 77 degrees F., 100 grams, 5 seconds, of approximately 20 according to the A. S. T. M. standard.

The stretchable webs which I employ are webs of paper which have been creped so as to be universally stretchable. Preferably, this is done in accordance with the teachings of Patent 2,008,181 in the name of Kemp. Any available papers meeting a standard of economy may be employed. I ordinarily employ kraft papers because of their availability and cheapness. The thickness of the webs may be considerably varied, and I ordinarily employ papers of between 15 lb. and 60 lb. basis weight.

It is important to bring the papers themselves into as intimate an association as possible with the surface of the discrete bituminous layer. Hence, I prefer to employ papers creped with relatively fine and uniform creping crinkles as distinguished from papers of corrugated, pleated or folded types wherein substantial areas of the paper webs might be out of contact with the bituminous layer. Fine and uniform creping crinkles, even with heavy papers, can be attained by creping the papers by means of a positive creping adhesive. This adhesive may be the bitumen used for the discrete waterproofing layer in my roofings or it may be some other substance capable of forming a good bond therewith and chosen for additional characteristics.

The exposed paper webs do not require to be waterproofed throughout their body since even plain paper webs directly exposed to the weather in my products exhibit a long-term water resistance, as set forth above. But the durability of the paper webs may be increased and the tendency to shrink may be decreased by saturating or coating them with protective substances of bituminous, waxy, resinous, rubbery or other characteristics, and this may be done prior to or as an incident of the creping operation.

In Figure 1, I have illustrated a roofing fabric which, insofar as it embodies a base of saturated felt 1, and a heavy discrete layer of bituminous coating 2, is similar to the prepared roofings of commerce. This product has, however, been treated by imposing upon the outer surface of the bituminous layer 2 a layer 3 which is a universally stretchable, gathered web, as set forth above. The addition of such a web has been found to add years of service to the product in the ways already described. The web 3 is the portion of the product directly exposed to the weather. It may, as indicated, be of untreated paper throughout its thickness, but it may if desired be waterproofed or saturated or colored or treated on the exposed surface with a coating of paint or lacquer or suitable binder containing metallic flakes, as in aluminum paint.

It has been found that the addition of such a layer protects the bituminous layer 2 from the progressive destruction which has been described. Contrary to expectations, the web 3 does not tend to expand by itself upon standing or weathering. On the contrary, it tends to maintain itself under slight tension, and if the roofing is exposed to weathering, including high temperatures, a tendency of the web 3 to pull slightly inwardly from cut edges of the product may be observed. There is no tendency, however, toward delamination providing the bituminous layer 2 is well-bonded to the stretchable layer 3.

The product illustrated in Figure 1 may be manufactured and sold in roll form or in the form of cut individual units. In smaller units, such as shingles or shingle strips, or even at the edges of roll roofing units, I may destroy the tendency of the web 3 to pull inwardly and also protect the edge of the felt by a method illustrated in Figure 2 where a stretchable web 3, larger in dimensions than the remainder of the roofing unit comprising the saturated felt 1 and the bituminous layer 2 has been employed, and where the extending edge of the web 3 has been brought around the edge of the roofing unit

and cemented back underneath, as at 3a. The cementing may be done with bitumen or with any other water-proof adhesive capable of making a good bond.

In Figure 3 I have shown a piece of roofing material manufactured entirely from a plurality of stretchable webs and a plurality of discrete, heavy layers of bitumen. The illustrated product comprises four layers of creped paper 4, 5, 6 and 7, and three layers 8, 9 and 10 of coating type bitumen. The product may, however, be made of three layers of paper and two intermediate layers of bitumen, or with a larger number of layers as may be desired.

In a product such as is illustrated in Figure 1, the saturated felt 1 serves to provide a base or support for the bitumen, but is itself deficient in weather resistance. Moreover, the exemplary product has but one layer of bitumen which can serve as a waterproofing membrane, although it may be made with more by plying. By contrast the product of Figure 3 contains in the illustrated embodiment three discrete heavy layers of bitumen serving as waterproofing membranes and providing a greatly prolonged life. The use of a plurality of layers of bitumen and intermediate and external layers of stretchable paper provides in itself a structure having sufficient body and strength for roofing uses, yet containing a plurality of bituminous layers capable of serving as a water and weatherproof membrane.

Certain other advantages are secured in such a product. The use of stretchable webs on both sides provides a product which not only is reversible in that it may be laid either side up, but also will not stick when wound into rolls. The use of talc or other material for preventing adhesion is obviated. The product, moreover, is as a whole more flexible than a prepared roofing of the same thickness and conventional construction.

This makes it possible for me to effect a seam construction as hereinafter set forth. The surfacing and intermediate layers of universally stretchable paper are effective in preventing cracking of the product when it is bent sharply at an angle. When laid upon a roof and fastened at both edges, it maintains itself bodily under slight tension which keeps it taut and prevents buckling or stretching. Yet the tension is so slight that it will not pull away from fastening means such as roofing nails, nor will it pull itself into wrinkles.

It has further been found that if the external layer of bitumen in a product such as shown in Figure 3 becomes, through the removal or destruction of the exposed layer 4 of stretchable paper, subject to progressive disintegration characteristic of heavy bituminous layers, this disintegration will stop as soon as it reaches an underlying layer of stretchable paper, again very greatly prolonging the life of the product.

While there is no tendency toward delamination in the product, the same phenomenon of the slight pulling back of the upper paper layer 4 at the edges of the product may be encountered and can be corrected in a similar way. In Figure 4 I have shown the product where the upper paper layer 4 has been caused to extend beyond a cut edge and has been folded over, brought back beneath the product, as at 4a, and adhesively secured as before. Yet another way of treating the edges of the product is shown in Figure 5 where an edge portion thereof has been bodily bent back upon itself and adhesively secured at 11. This is a treatment which may be used both for roll roofing and for individual units such as shingles which may if desired be rolled or turned on all exposed edges, it being unnecessary to do this at the end of the product which will be lapped by other shingles or units. The turned edges may merely be adhesively secured or they can if desired be held by any suitable fastening means such as rivets, staples, or the like.

In manufacturing a product such as illustrated in Figures 3 to 5, I prefer to crepe the paper by means of the bitumen to be used as the waterproofing membrane. I have given above thicknesses of bitumen capable of serving as the discrete heavy layers contemplated by this invention. In accordance with the teachings of my Patent No. 1,782,767, dated November 25, 1930, entitled Creping Process, it is not difficult to crepe papers bearing asphaltic or other bituminous layers of the required thicknesses. It will be understood however that coatings for creping are usually imposed upon the plain paper; hence the thickness of the coating is increased by the amount of gathering imparted to the paper in the creping

process. If the paper is creped so as to acquire 25% stretchability in each direction, 57% is added to the weight or thickness of the initial bituminous coating. Similarly, if the paper is creped so as to acquire 33½% stretchability in each direction, 77% will be added to the weight or thickness of the coating. These factors may be taken into account in applying the initial coating of bitumen to the paper. Again, the thickness of the coating between layers of creped paper will, of course, be doubled if the creped paper layers are plied with their coated sides next each other. In manufacturing products such as are shown in Figure 3, I ordinarily form two layers of coated paper and adhesively secure them together with the coated sides in contact. The resultant product will be of sufficient strength and resistance to stretching to permit the application of a heavy coating of asphalt for the reception of additional layers of coated creped paper. In making a 4-ply product, I may first manufacture two 2-ply products, coat each and ply them together with their coated sides in contact.

In the application of built-up roofings, my products present further advantages and economies. It will be understood that the efficacy of a built-up roof if properly laid will depend upon the number of continuous waterproofing membranes which it contains. Since the upper or surface membrane is subject to the disintegration which I have described, and since the saturated felt is not itself satisfactorily weather resistant, it is the general practice to cover all portions of a roof deck with a plurality of layers of saturated felt, and intermediate layers plus a top layer of mopped asphalt. The mopping of layers of felt onto a roof deck and onto each other is an arduous and inconvenient task, the results of which are greatly affected by the skill of the workman and weather conditions. Moreover, the result may be made unsatisfactory by overheating the asphalt in the kettle whereby its weather resistance may be impaired and by failing to apply the felt layer to a mopped-on coating at a time when the asphalt is sufficiently tacky to form a good bond. Blisters in built-up roofs are not uncommon.

In laying a built-up roof from a product such as illustrated in Figure 3, it may be noted that the product already contains a plurality of bituminous membranes. These were formed at the factory under conditions of careful temperature control. They will be more uniform and more dependable than membranes formed by mopping on the job. Because of the plurality of membranes built into my product, the laying of a built-up roof is simplified. Fewer layers and fewer moppings will be employed, and it is usually sufficient to use a single layer of a product of suitable thickness. Thus in Figure 6 I have shown adjacent pieces 12 and 13 of my product mopped onto a concrete deck 14 with a suitable cemented lap as at 15. It will be understood that on a wood deck 55 fastening means, such as nails, will be employed to hold an edge of one piece which edge including the fastening means will then be lapped by an edge of the adjacent piece.

It will not be necessary to provide my built-up roof with a top mopping of bitumen. If, however, the roof is to sustain traffic, it may be desired to top mop it, as at 16 in Figure 6, and to provide it with a covering of granular material, as at 17. This may be done without detriment to the roof or its weather resistance.

The extraordinary flexibility of my products such as shown in Figure 3 makes possible the formation of various types of adhesively united seams. In Figure 8 I have shown at 18 a piece of my fabric prepared for seam formation. The side of the fabric shown is that which will be the under side in use. Along one edge I provide a band 19 of suitable waterproof adhesive material. This material may be a pressure-sensitive, solvent-sensitive or thermoplastic adhesive of waterproof nature. Asphalt is an entirely satisfactory material. When used, it may be applied hot and immediately covered with a strip 20 of cellophane or similar material.

It is characteristic of this combination that the cellophane or similar non-fibrous film may readily be removed from the band of adhesive by a quick jerking movement, although with a suitably tenacious asphalt, it is not capable of being readily peeled away. It may be removed by peeling if it is first wet with water. Removal by a jerking movement is most convenient.

At the other edge of the fabric 18, I provide another 85 band of similar adhesive but of lesser width, as at 21.

This is also covered with a strip 22 of cellophane or the like. Inwardly of the edges of the adhesive bands 19 and 21, I prefer to score the material to facilitate bending.

The material of Figure 8 may be made continuously as indicated in Figure 7. Here the material, moving in a direction of the arrow, is first passed between rotary scoring devices 23 and 24, and is next coated with the adhesive. This may be done by providing a pan 25 of asphalt or other suitable material (together with heating means as may be required), an applicator roll 26 and a series of transfer rolls 27. An anvil roll 28 may be employed to support the fabric during the coating.

Coating may be applied to form the strips 19 and 21 in other ways. By way of example, it is within the scope of my invention to spray onto the surface of the fabric 18 a heat softened bitumen or other adhesive, or to apply by spraying an artificial latex or dispersion of such material. The cover strips, one of which is indicated at 22 at Figure 7, are withdrawn from rolls as at 29 and applied by squeeze rolls 30 and 31. The product treated in this fashion may be wound into suitable rolls for shipment.

In laying the product, the side to which the adhesive has been applied is disposed downwardly, but the edges are turned up on the score lines and the cover strips 20 and 22 are removed. In Figure 9 I have shown two adjacent pieces of roofing at 32 and 33. The edge portions are turned up as at 34 and 35 and are brought together with their coated sides in contact. A completely tight seam may be formed between these juxtaposed edges by pressing them together, with an application of heat if required to reactivate the adhesive, or with an application of solvent. The pressing may be done by rollers 36 and 37 mounted on pivoted arms 38 and 39 by which the rollers may be pressed strongly together and by which they may be moved along the seam. It will be noted as an advantage of this procedure that the edges of the fabric are pressed directly together and thus are brought into positive contact. This is to be distinguished from an operation in which the edges of roofing fabric are merely lapped and are pressed against a roof deck. In such an operation inequalities in the roof deck may relieve the pressure over certain areas, interfering with full contact.

After a seam has been made as illustrated to the right in Figure 9, the entire standing portion of the fabric may be laid over as shown at the left-hand end of the figure. Because the portion 34 of the fabric is narrower than the portion 35, it will be seen that a coated edge of the fabric piece 35 projects freely and may be used to fasten the laid-over seam construction against the fabric piece 32. Adhesion may be effected by running a pressure roller 40 along the edge of the seam formation, with or without the application of heat or solvent as may be required.

Prior to the laying over of the standing seam construction, the marginal portions of the fabric piece 32 may be fastened to the roof deck, if of wood, as by fastening nails or the like 41 in Figure 10.

5 The fabric 18 may be prepared with covered lines of adhesive for the formation of other types of seams as will now be evident.

Modifications may be made in my invention without departing from the spirit of it. Having thus described my invention in certain exemplary embodiments, what I claim as new and desire to secure by Letters Patent is:

10 1. A prepared roofing fabric consisting of a plurality of heavy, continuous, discrete layers of bituminous substance, each capable of serving as a waterproof membrane, and each having a weight of not less than about 8 to 10 pounds per 100 sq. ft., said layers being separated from each other by universally stretchable creped webs of paper in intimate adhesive association therewith, there being layers of universally stretchable crepe paper forming the outer surfaces of the fabric, and means for the formation of seam structures in adjacent fabric pieces, said means comprising a coating of adhesive substance on a marginal portion of the roofing fabric, said coating being covered by a removable protective strip.

15 2. The structure claimed in claim 1 wherein the fabric is scored for bending along a line adjacent to the edge of said coating.

20 3. The structure claimed in claim 1 wherein the fabric is scored for bending along a line adjacent to the edge of said coating, and in which said adhesive comprises bitumen, and said covering is a removable strip of nonfibrous film substance.

25 4. The structure claimed in claim 1 prepared for seam formation and bearing strips of adhesive adjacent opposite marginal edges of the reverse face of the fabric, said strips being of unequal width.
